UNITED STATES PATENT OFFICE.

HARLEIGH GILLETTE, OF CHICAGO, ILLINOIS.

ELECTRIC CLOCK.

1,078,274.

Specification of Letters Patent. Patented Nov. 11, 1913.

Application filed October 21, 1912. Serial No. 726,890.

To all whom it may concern:

Be it known that I, HARLEIGH GILLETTE, a citizen of the United States, residing at Chicago, in the county of Cook and State 5 of Illinois, have invented a new and useful Improvement in Electric Clocks, of which the following is a specification.

My invention relates to an improvement in the class of electric-clock systems wherein 10 a master-clock actuates a secondary clock, in circuit with it, at uniform intervals, and an electric cut-out device is interposed in the circuit.

The primary object of my invention is to 15 economize in electric current by opening the circuit instantaneously, after each closure thereof by the master-clock, through the medium of a double-contact device in the circuit with a double cut-out device extraneous of the secondary clock and adapted 20 to control any desired number of secondary clocks in said circuit.

In the accompanying drawings, Figure 1 is a view in vertical sectional front elevation 25 of a secondary electric clock; Fig. 2 is a broken plan view showing a pawl-locking device for the minutes-wheel of the secondary-clock train; Fig. 3 is a broken section on the irregular line 3, Fig. 2; Fig. 30 4 is a view in front elevation of the electric cut-out device; Fig. 5 is a section on the irregular line 5, Fig. 4; Fig. 6 is a view in elevation of a double-contact device actuated by the primary clock; Fig. 7 is an 35 enlarged section on line 7, Fig. 6; Fig. 8 is a broken section on line 8, Fig. 7, and Fig. 9 is a diagrammatic view showing the master-clock, with the contact device, the cut-out device and a series of secondary clocks 40 included in an electric-generator circuit.

Any known or suitable construction of secondary electric clock 10 may be used, but the construction thereof illustrated in Figs. 1 to 3, inclusive, is preferred, and is described as follows: The frame comprises a 45 rear plate 11 and a similar front plate 12, both widening toward their lower ends, as shown of the plate in Fig. 1, and connected by three spacing-members, as shown at 13. The clock-train includes the minutes-wheel 50 14 in ratchet-form, above which is supported, on the inner face of the front frame-plate, an electromagnet 15 having terminals of its coils connected by insulated wires 6 16 and 17 respectively with brass strips 18 and 19 on an insulating block 20 secured upon

the uppermost spacing-member 13 and carrying a condensing-coil 21, having its terminals connected with the strips 18 and 19, respectively. The armature 22 of the electromagnet is secured at one end on a rock-shaft 23 journaled on the frame-members to extend across the pole-piece of one spool and adjacent to a side of the pole-piece of the other spool. To the under side of the pivotal armature is rigidly secured a brass bar 24 having a downwardly-inclined rear-end section 24¹ extending adjacent to an adjustable stop 25 screwing transversely through a longitudinally-split stud 26 projecting from the inner face of the frame-plate 12. The bar 24 inclines slightly in a downward direction toward its opposite, forward end, where it carries pivotally a pawl 27 to engage the teeth of the minutes-wheel and having a spring-connection 28 with the bar. A pivotal detent is shown at 29 for the wheel 14. A longitudinally-split stud 30, projecting from the frame-member 11, has a screw 31 extending transversely 30 through it into the path of the free end of the pawl 27, toward which it inclines. The purpose of this screw is to afford an adjustable lock for the pawl to prevent the wheel 14 from being turned by jarring or 35 momentum beyond the extent of one tooth with each drop of the armature when released by de-energizing the electromagnet, after it has been energized as hereinafter described. This is effected by the pawl, in its movement against the wheel to turn it, encountering the inner end of the screw, which binds it against the upwardly-inclining edge of the adjacent wheel-tooth and thus wedges it against the wheel to lock the 40 latter against undue turning, thereby assuring accuracy in the work of the minutes-hand (shown dotted in Fig. 9) on the shaft 14¹ carrying the wheel 14.

Of the master-clock, which may be of ordinary general construction and therefore requires no detailed illustration or description herein, only the escapement is shown (Fig. 9). The seconds-wheel 32 is shown to be provided about its shaft with a pinion 33 meshing with a toothed wheel 34 of twice the diameter of that of the pinion, journaled directly below the latter and carrying a stud 35 eccentric of and closely adjacent to its shaft 36 to coöperate with the double-contact device 37 illustrated in detail in Figs. 6 to 8, inclusive, and described as follows:

5 A bracket 38, of general T-shape, adapted to be securely fastened to suitable supports 39, 39 below the master-clock, carries at opposite sides of the transverse center of its head-portion, and suitably insulated therefrom, L-shaped bearings 40, 40 for opposing adjustable contact-points 41, 42, between which works pivotally, as hereinafter explained, a contact-head 43. The bracket has 10 secured to the face of its stem-portion, near the upper, laterally-enlarged end thereof, an arm 44 provided in its outer angular end with a screw-bearing 45 for one end of a pivot-shaft 46, the opposite end of which 15 engages a similar bearing 45¹ provided in the bracket 38. The shaft 46 carries a switch-arm 47 having a bifurcated upper end, at which it embraces the stud 35, this arm being formed on its lower end with a 20 forward hook-shaped projection 48, against diametrically-opposite points in the under surface of which about pivotally the pointed ends of a fork 49 carried by the head 43. This head is held in its pivotally-snapping engagement with the projection 48 by a 25 spiral spring 50 resiliently tying it to the shaft 46.

From the foregoing description of the device 37, it will be seen that the head 43 is 30 always in contact with one or the other of the points 41, 42, and that turning the arm 47 to carry the forked head 43 beyond the dead-center between the two contact points permits resilient buckling action on the head 35 of the spring 50 to snap the head against the contact-point opposite the one toward which it is so carried.

The double cut-out device 51 is constructed as most clearly shown in Figs. 4 and 5. 40 On a suitable base 52, of insulating material, occupying the position relative to the master-clock and device 37 represented in Fig. 9, and extraneously of the secondary clocks, are supported two electromagnets 53 and 45 54 having a common armature 55 pivotally supported midway between its ends on a bracket 56 secured to the face of the base to carry the electromagnets. The armature extends across the pole-pieces of the two innermost spools and between the pole-pieces of the two outer spools, with its ends closely adjacent to the last-named pole-pieces. Between the two inner spools the armature has rigidly secured to its under side a brass 50 block 57, from which depends a bifurcated switch-finger 58, preferably of copper, formed with a forwardly-projecting angular head 58¹ yieldingly supported by a spiral spring 59 confined against it by a depending 55 screw 60 surrounded by the spring and passing centrally through the angular head to work in the block 57 for adjusting the tension of the spring. On the base 52, in the path of the bifurcated lower-end portion of 60 the finger 58, are contact-members 61 and 62,

separated by an intervening space at their opposing ends, and fastened to the base, respectively, by binding-posts 63 and 64, with which the terminals of the inner magnet-spoils are connected, those of the outer spoils being respectively connected with binding-posts 65 and 66 on plates 67 secured on the base. The head 58¹ has an insulated-wire connection at 68 with the metal bracket 56. 70

As will be understood from the foregoing description, by alternately energizing the electromagnets 54 and 53, the resultant rocking movements of their armature turns the finger 58 from one to the other of the contact-members 62, 61, thereby cutting out of circuit one of the electromagnets; and in the event of the finger becoming obstructed from any cause, as by corrosion, causing it to adhere to a contact-member, its resiliency due 80 to the spring 59 will, under the armature-movements, force its separation from such contact-member. 85

In use, my improved double-contact and double cut-out devices are included with a 90 master-clock and two secondary clocks (the number of which latter may, however, be any desired), in an electric circuit, which may be traced on the diagrammatic representation in Fig. 9, as follows: from one 95 pole of a generator, indicated at 69, over wire w to the armature 55, from the opposite generator-pole over wire w^1 through the electromagnets 15 of the series of secondary 100 clocks to the pivot-shaft 46 of the arm 47, over wire w^2 connecting one bearing 40 with the metal plate 67 carrying the binding-post 65, and wire w^3 connecting the other bearing 40 with the similar plate carrying the binding-post 66. 105

The operation is as follows: With the parts in the relative positions represented in Fig. 9, the circuit is broken at 70 and 71. Each complete rotation of the seconds-wheel 32 will turn the shaft 36 through a 110 half-revolution. In the half-revolution of the wheel 34 from the position illustrated, the stud 35 is carried about the shaft 36 to bear against the side of the bifurcated end of the arm 47 opposite that against which it is shown to bear in the drawing. Continued movement of the stud turns the arm 47 past the dead-center, whereupon the spring 50 snaps the pivotal head 43 against the contact-point 42. This closes the circuit over wire w , arm 58, through electromagnet 54, wire w^3 , arm 47, and wire w^1 , thereby energizing the electromagnet 15 of each secondary clock to attract its armature. This closure of the circuit also energizes the 120 electromagnet 54 of the device 51 to attract the armature 55 and thus turn the finger 58 into engagement with the contact-member 61, thereby opening the circuit and de-energizing the electromagnet 15, whereupon 125 130

the armature 22 drops to cause the pawl 27 to actuate the minutes-wheel 14 and the minutes-hand to register one minute. When, in the continued rotation of the seconds-wheel of the master-clock, the wheel 34 completes another half-revolution, the stud 35 acts in the same way against the opposite side of the bifurcated end of the arm 47 to snap the head 43 against the contact-point 42, thereby closing the circuit over wire w , through electromagnet 53, over arm, 58, wire w^2 , arm 47, and wire w^1 , to again energize the (or each) electromagnet 15, and the electromagnet 53 to turn the finger 58 into engagement with the contact-member 62, thus again opening the circuit and causing, in the manner described, another movement of the (or each) secondary-clock minutes-hand. It will thus be seen that each time the circuit is closed to energize the secondary-clock electromagnet, it remains closed only for an instant, when it is opened and kept open during nearly the entire minute-intervals, thereby greatly economizing electric current. The circuit remains closed only long enough to attract the armatures. The electromagnet 15 acts momentarily ahead of the electromagnet 53 or 54 in circuit with it, in attracting its armature 22, because it differs from them in the number of turns in its coil.

I realize that considerable variation is possible in the details of construction thus specifically shown and described, and I do not intend by illustrating a single specific or preferred embodiment of my invention to be limited thereto; my intention being in the appended claims to claim protection upon all the novelty there may be in my invention as broadly as the state of the art will permit.

What I claim as new and desire to secure by Letters Patent is:—

1. In combination with a master-clock and a secondary electric clock having an electromagnet and an armature-driven minutes-wheel, an electric circuit containing said electromagnet, a double electric-contact device in said circuit actuated by the master-clock to operate said secondary clock, and a double electric cut-out device having its own electromagnets in the circuit, actuated by each operation of said contact-device to open the circuit.

2. In combination with a master-clock and a secondary electric clock having an electromagnet and an armature-driven minutes-wheel, an electric circuit containing said electromagnet, a double electric-contact device in the circuit, comprising opposing contact-points and a contact-making pivotal device working in opposite directions between them by successive complete rotations of the master-clock seconds-wheel to close the circuit by each movement of said device and

operate said secondary clock, and a double electric cut-out device having its own electromagnets in the circuit, actuated by each operation of said contact-device to open the circuit.

3. In combination with a master-clock having a seconds-wheel, and a secondary electric clock having an electromagnet and an armature-driven minutes-wheel, an electric circuit containing said electromagnet, an eccentric stud driven by said seconds-wheel about a central axis to make a half-revolution in each complete rotation of the seconds-wheel, a double electric contact-device in the circuit having a pivotal bifurcated switch-arm embracing said stud, and a double electric cut-out device having its own electromagnets in the circuit actuated to open the latter by each throw of said arm.

4. In combination with a master-clock having a seconds-wheel carrying concentrically a pinion, and a secondary electric clock having an electromagnet and an armature-driven minutes-wheel, an electric circuit containing said electromagnet, a toothed wheel of twice the diameter of and meshing with said pinion and carrying an eccentric stud, a double electric-contact device in the circuit, having a pivotal bifurcated switch-arm embracing said stud, and a double electric cut-out device having its own electromagnets in the circuit actuated to open the latter by each throw of said arm.

5. In combination with a master-clock having a seconds-wheel, and a secondary electric clock having an electromagnet and an armature-driven minutes-wheel, an electric circuit containing said electromagnet, an eccentric stud driven by said seconds-wheel about an axis to make a half-revolution in each complete rotation of the seconds-wheel, a double electric-contact device in the circuit, comprising a pair of opposing contact-points, a pivotal bifurcated switch-arm embracing said stud, and a contact-making spring-snapped head pivotally connected with said arm to work between the contact-points and close the circuit by each movement of said arm, and a double electric cut-out device having its own electromagnets in the circuit actuated to open the latter by each throw of said arm.

6. In combination with a master-clock having a seconds-wheel and a secondary electric clock having an electromagnet and an armature-driven minutes-wheel, an eccentric stud driven by said seconds-wheel about an axis to make a half-revolution in each complete rotation of the seconds-wheel, an electric circuit containing said electromagnet, a double electric-contact device in the circuit, comprising a bracket carrying opposing contact-points, a pivotal switch-arm having one end bifurcated and provided with a bearing-finger on its opposite end,

and a forked contact-head between said points having a spring-connection with the arm-pivoting shaft abuttingly holding said head pivotally against said finger, and a double electric cut-out device having its own electromagnets in the circuit actuated to open the latter by each throw of the switch-arm.

7. In combination with a master-clock and a secondary electric clock having an electromagnet and an armature-driven minutes-wheel, an electric circuit containing said electromagnet, a double electric-contact device in said circuit actuated by the master-clock to operate the secondary clock, and a double electric cut-out device comprising two electromagnets and a pair of spaced contact-members interposed in the circuit between said clocks, each contact-member being connected with one electromagnet, and a pivotal armature for said electromagnets having a switch-finger extending from it to engage said contact-members alternately by the movements of the armature.

8. In combination with a master-clock and a secondary electric clock having an electromagnet and an armature-driven minutes-wheel, an electric circuit containing said electromagnet, a double electric-contact device in said circuit actuated by the master-clock to operate the secondary clock, and a double electric cut-out device comprising

two electromagnets and a pair of spaced contact-members interposed in the circuit between said clocks, each contact-member 35 being connected with one electromagnet, a pivotal armature for said electromagnets and a switch-finger spring-connected with said armature to extend therefrom and engage by its movements said contact-members 40 alternately.

9. In combination with a master-clock and a secondary electric clock having an electromagnet and an armature-driven minutes-wheel, an electric circuit containing said 45 electromagnet, a double electric-contact device in said circuit actuated by the master-clock to operate the secondary clock, and a double electric cut-out device comprising two electromagnets and a pair of spaced 50 contact-members interposed in the circuit between said clocks, each contact-member being connected with one electromagnet, a pivotal armature common to both electromagnets, and a bifurcated switch-finger 55 having a pivotal spring-connection with said armature to extend therefrom and engage by its movements said contact-members alternately.

HARLEIGH GILLETTE.
